UNITED STATES PATENT OFFICE.

GEORGE L. WILLIAMS AND HENRY RUNDLE, OF EDWARDSVILLE, ILLINOIS,
ASSIGNORS OF ONE-THIRD TO JAMES T. COOPER, OF SAME PLACE.

FIRE-ESCAPE.

SPECIFICATION forming part of Letters Patent No. 252,829, dated January 24, 1882.

Application filed May 31, 1881. (No model.)

To all whom it may concern:

Be it known that we, GEORGE L. WILLIAMS and HENRY RUNDLE, residents of Edwardsville, Illinois, have jointly made a new and useful Improvement in Fire-Escapes, of which the following is a full, clear, and exact description, reference being had to the annexed drawings, making part of this specification, in which—

Figure 1 is a view in perspective, showing 10 the improvement as arranged in use; Fig. 2, a side elevation of the traveler; Fig. 3, an edge elevation of the traveler; Fig. 4, a side elevation of the traveler, the side plate being turned around on its pivot, showing the interior of the construction, the brake or tightener being closed against the rope; Fig. 5, a 15 sectional elevation of the traveler, the brake being set against the rope; Fig. 6, a sectional elevation of the traveler, the brake being released from the rope; Fig. 7, a view of the device used in attaching the rope to its point of support, and Fig. 8 a section taken on the line x x of Fig. 5.

The same letters denote the same parts.

25 The present invention is an improvement in that class of fire-escapes which are portable, occupying but little space comparatively, when packed, and which can be readily attached to any part of a building from which an escape 30 is likely to be needed.

Considered generally, it consists mainly of a rope, which in use is fastened to the building at the point from which the descent is to be made, and a traveler which moves upon the 35 rope, and to which the person, in descending, is connected.

The improvement relates more especially to the device used in fastening the rope to its point of support, and to the construction of the 40 traveler and mode of connecting it with the rope.

A hook, A, is attached to or provided with a plate, B. The latter is perforated to receive a screw, C, which is passed through the opening in the plate, and then screwed or driven into the support for the escape, which support may be any fixture in or about the part of the building from which the descent is to be made, suitable for receiving the screw. Ordinarily 50 the window-jamb D is best suited for this pur-

pose. The screw is provided with a shoulder, c, causing the plate, when the screw is driven home, to be confined closely against the bearing-point. This prevents the strain of the escape, applied as it is immediately alongside 55 the jamb D, from exerting a leverage upon the screw, as would occur if the plate were allowed to slip outward on the screw from the jamb, or whatever surface the screw may be held in. The screw is furnished with a handle, c', to enable it to be readily inserted in the bearing D. The hook A is jointed to the plate B to more effectually prevent the plate B from being drawn outward from the jamb.

The rope E may be attached directly to the 60 hook A, but is preferably provided at its upper end with a hook, F, which in turn is made to engage with the hook A. The rope E is supposed to be of sufficient length to reach to the ground.

G represents what, for convenience, we term the "traveler." It is made up substantially of three parts—a frame, H, having a pair, I I', of double roller bearings or sheaves, a braking device, J, pivoted to the frame H at h, and 75 having a roller-bearing, K, and a bearing, L, and a brake-lever, M, pivoted to the frame H at m, and consisting of the eccentric m' and lever m².

The sheaves I I' at one side are journaled in 80 the frame H, and at the other side in a crescent-shaped plate, I², which in turn is held in place by means of the part I³, which connects it with the frame H. The part I³ also forms a bearing for the rope E between the sheaves I 85 and I'. The part I³ also serves to hold a shoe, N, which, by means of a set-screw, n, can, as desired, be set out against the rope E, and thus enable the brake-roller K to exert the proper pressure upon the rope as the latter becomes worn.

The traveler G is attached to the rope by winding the latter around the sheaves I I', as indicated in Figs. 1, 6. The brake J is then set against the rope, bringing the parts into 95 the position shown in Figs. 4, 5, the brake being held against the rope by means of the lever M, which, when closed, sets the eccentric m', so that its center is past the point of bearing upon the back j of the brake J. A side- 100

plate, O, pivoted to the frame at o, serves to inclose the rope E laterally in place, the plate, after the rope has been wound around the sheaves I I', being swung around and fastened by means of the spring-catch o' engaging in the notch o². The frame H is provided with a shank, P, terminating in an eye, p. By grasping the shank P and lever m² the brake can be easily closed against the rope, which now bears upon the pulleys I I', bearing I³, roller K, and bearing L. A sling, Q, by means of a hook, q, is hung in the eye p of the traveler. In use the person desiring to descend adjusts the sling Q under his arms and around his body, and with his hands regulates the pressure of the lever m² and brake J upon the rope E. To hasten the descent, the brake is loosened, allowing the traveler and the person suspended therefrom to slide downward upon the rope more freely, and by closing the brake against the rope the descent is checked. By throwing the eccentric m' past its center, as shown in Fig. 4, the brake will remain closed, however much the rope is strained. Hence after the brake has thus been set the user of the escape need no longer maintain his hold particularly upon the brake lever.

The sling Q may be furnished with hooks R R, for the purpose of attaching articles which the person descending may wish to take along:

In place of fastening the rope to the hook A and allowing the traveler to move down upon the rope, the traveler, by means of the shank P and eye p, may be attached to the hook A and the rope fed downward through the traveler. In such case the sling is attached to the rope, and a person stationed above regulates by means of the traveler the descent of whatever may be attached to the rope. By closing the lever M, so that the center of the eccentric

m' is past the point of bearing upon the brake, a person can descend safely without the co-operation of an assistant above.

The plate O serves both to hold the rope laterally in place upon the sheaves I I' and as a tie 45 when the lever M is forced against the brake J and sheaves I I' to resist the strain crosswise upon the traveler. The bearings I I' and K, or either of them, may be fixed; but it is better to make them in the form of rollers, as shown. 50 The brake J is furnished with a lip, j', to better hold the brake in place as it is turned on its pivot h. There may be another bearing, L', on the brake for the rope.

We claim—

1. The combination of the bearing D, the plate B, the screw C, having the shoulder e, the hook A, jointed to the plate B, the rope E, and the traveler G, substantially as described. 55
2. The traveler G, combining in its construction the frame H, the sheaves I I', the brake J, having the roller K, and the cam-lever M, substantially as described. 60
3. The combination of the frame H, the sheaves I I', the part I³, the plate I², the shoe 65 N, the screw n, the brake J, bearing K, and lever M, substantially as described.
4. The combination of the frame H, sheaves I I', brake J, roller K, bearing L, and lever M, substantially as described. 70
5. The traveler G, having fixed or movable bearings at I I', the brake J, pivoted at h, and having a fixed or movable bearing at K, the cam-lever M, and the plate O, substantially as described.
